UNITED STATES PATENT OFFICE.

KIICHIRO TOYODA, OF SHIRAKABECHO, NAGOYA, JAPAN.

TAIL-THREAD-CUTTING MECHANISM IN AUTOMATIC LOOMS.

Application filed April 11, 1927. Serial No. 182,776.

My invention relates to a mechanism for cutting the tails of the filling thread left at the selvage of a fabric upon the weft replenishing operation in an automatic loom.

5 In the old devices employing a continuously moving cutter, the latter is subjected to continuous wear so that it must be frequently renewed. The object of the present invention is to overcome such disadvantage 10 and to provide a mechanism wherein the cutter is effectively actuated only twice immediately after the completion of the weft replenishing operation, and the cutter being normally held inoperative, so that the cutter 15 is not subjected to continuous wear and therefore can be used for a long time.

In the drawings, illustrating what I now consider the preferred form of my invention,

20 Figure 1 is a side view of certain parts of an automatic loom comprising my new mechanism;

Figure 1^a shows a continuation of the rod 8 with the operating mechanism therefor.

Figure 2 is a plan view thereof, and

25 Figure 3 a fragmentary view similar to Figure 1, showing the cutting mechanism in its operative position.

In the drawings, 1 is the slay, 2 the slay sword, and 3 a projecting engaging member 30 attached thereto. Journalled in the loom frame (shown in chain lines) is a shaft 4 which is operatively connected to the shuttle ejecting rod (not shown in the drawings), and it has an operating lever 5 fixed thereto.

35 Connected to the lower end of the operating lever 5 is a receiving rod 6 adapted to cooperate with the engaging member 3. This receiving rod is operatively connected to weft detecting devices, and is normally below the 40 path of the engaging member 3 on the slay sword, as shown in full lines in Figure 1, but is raised upon the breaking or failure of the filling threads, to the position shown in chain lines. Thus, as the slay moves forward, the

45 said receiving rod 6 will be actuated by the projecting engaging member 3, and will rotate the operating lever 5 into the position shown in chain lines, actuating the shuttle ejecting rod to effect the transfer of a fresh 50 shuttle.

To the fulcrum pin 7 connecting the receiving rod 6 and the operating lever 5 is connected the forward end of the operating bar 8. The other end of said bar is slidably 55 mounted upon a block 10 which is pivotally mounted on a part 9 of the frame. The block

10 is engaged by a cam 12 fixed on the tappet shaft 11, and is adapted to be raised or lowered thereby. The cam 12 is designed in such a manner that the block 10 is held in its 60 raised position during one half rotation of the cam and then in its lowered position during the remaining half rotation of the cam. It should be noted that the slay makes two beats during one rotation of cam 12. A hook 65 28 is mounted at an intermediate point of the operating bar 8. On the rear side of the slay sword is attached an engaging member 29 adapted to engage with the hook 28. As the cam 12 rotates, the block 10 will be oscillated 70 up and down, thereby raising and lowering the operating bar 8 together with the hook 28. As previously mentioned, this movement takes place in such a manner that the operating bar 8 is held in raised position during one 75 half rotation of the cam and then held in lowered position during the remaining half rotation of the cam.

During a shuttle changing operation, as the lever 5 and rod 6 are brought to the operative position as shown in chain lines in Fig. 1, the hook 28 will be also brought to its position shown in chain lines. Therefore, upon the first backward movement of the slay sword, the engaging member 29 thereon will 80 not engage with the hook 28 which is held raised by the cam, so that the operating lever remains in the position shown in chain lines. During the next half rotation of the cam 12, the block 10 and thereby the hook 28 will be 85 held in the lowered position. So, upon the next backward movement of the slay, the engaging member 29 will engage with the hook 28, thereby actuating the operating bar 8 to retract the operating lever 5 to the normal 90 position. Thus, it will be seen that, after the completion of the shuttle changing operation, the operating lever 5 is still held in its 95 operative position during two forward beats of the slay. 100

Mounted on the breast beam 13 is a shaft 14, to which are fixed a latch 15 and a lever 16. To the lever 16 is connected a link 17 which in turn is connected to the operating lever 5 by means of a slot 18 in the link and a pin 19 on the operating lever 5. The latch 15 is provided with a hook 20 and is normally raised by means of a spring 21. 105

As the operating lever 5 is moved to its operative position as shown in chain lines 110 in Figure 1, it pulls down the link 17, whereby the latch 15 will be pulled downwardly

against the action of the spring 21. As the operating lever 5 returns to its normal position, the latch 15 will also be returned to its raised position under the action of the spring 21.

Mounted on the temple rod 22 is a temple 23. Slidably mounted on one end of the temple 23 is a thread cutter 24 for cutting tail threads, which cutter is adapted to be pushed outwardly by the action of a spring 26 connected to the engaging lever 25. But normally the cutter 24 is held retracted by the engagement of the hook 20 on the latch 15 with the engaging lever 25. Attached to the front side of the slay is a leather pad 27 adapted to engage with the lever 25.

The operation of the invention is briefly as follows:—

When the weft detecting mechanism calls for a change of shuttle, the operating lever 5 is rotated to its operative position as shown in chain lines in Figure 1. Then, the latch 15 being pulled downwardly releases the engaging lever 25, whereby the cutter 24 is pushed outwardly, as shown in Figure 3. At the end of the forward movement of the slay, the leather pad 27 will engage with and push the engaging lever 25, thereby actuating the cutter 24 inwardly against the action of the spring 26. Thus, the cutter cuts the tail of the weft thread left at the selvage of the fabric.

As the operating lever 5 returns to the normal position, the latch 15 will be raised so that upon the next forward movement of the slay the engaging lever 25 will be caught by the hook 20 on the latch 15, whereby the cutter 24 is again held in normal position.

Now, as hereinbefore described, the operating lever 5 is made to still remain in its operative position during one rotation of cam 12 after the initiation of the weft replenishing operation. Consequently, the latch 15 still remains in its lowered position also for one rotation of the cam after the weft replenishing operation is initiated, and it returns to its raised position upon next rotation of the cam since the part 29 does not engage hook

28 on the first backward beat after the replenishing operation has been initiated. Thus, it will be seen that according to this invention the cutter 24 operates only twice, first to cut the tail thread leading to the exhausted shuttle, and second to cut the tail thread left by the fresh shuttle, the cutter being normally held in the inoperative position. As apparent from the foregoing, the cutter 24 is not subjected to continuous wear, since it does not partake of any unnecessary movement as in the earlier devices.

Whilst I have described the invention as applied to the automatic loom of the shuttle-changing type, it is to be understood that the invention is equally applicable to the automatic loom of the cop-changing type.

What I claim is:—

1. In an automatic loom comprising a weft-replenishing mechanism, the combination with the slay and the temple, of a thread cutter slidably mounted in said temple, an engaging lever in the path of said slay connected to said cutter, a means connected to said engaging lever for pushing out said cutter, an operating lever forming a part of said weft replenishing device, a latch operatively connected with said operating lever and normally engaging said engaging lever for holding said cutter in its inoperative position, said operating lever when moved to its operative position causing said latch to release said engaging lever, means including a cam for returning the operating lever and the latch to normal position after two forward beats of the slay and thereby causing said cutter to be twice operated by the slay by means of said engaging lever so as to cut the tail thread leading to the exhausted shuttle and the thread left by the fresh shuttle.

2. The combination as specified in claim 1 including an operating bar for said operating lever held in raised position for one-half revolution of said cam, said bar carrying a hook adapted to be engaged by an engaging member upon the slay.

In testimony whereof I affix my signature.
KIICHIRO TOYODA.
